By Milton E. Robinson

ATTORNEY.

UNITED STATES PATENT OFFICE.

MORTIMER G. MERRITT, OF ROME, NEW YORK.

DESIGN FOR A BICYCLE-RACK.

SPECIFICATION forming part of Design No. 36,091, dated September 30, 1902.

Application filed August 4, 1902. Serial No. 118,414. Term of patent 7 years.

To all whom it may concern:

Be it known that I, MORTIMER G. MERRITT, a citizen of the United States, residing at Rome, in the county of Oneida and State of New York, have invented and produced a new, original, and ornamental Design for a Bicycle-Rack, of which the following is a specification, reference being had to the accompanying drawing, forming a part hereof.

10 The figure is a perspective view of a bicycle-rack embodying my new design.

The features of the design are the form and arrangement of the part constituting the rack—that is to say, sets of parallel base-bars 15 *a*, sets of parallel upright bars *b*, curved par-

allel risers *c*, and connecting-bars *d*, *e*, and *f*, the curved risers *c* terminating in scrolls *c' c'*.

Having described my invention, what I claim as new, and desire to secure by Letters Patent, is—

20 The ornamental design for a bicycle-rack, substantially as herein shown and described.

In witness whereof I have signed my name to this specification, in the presence of two witnesses, this 25th day of July, 1902.

MORTIMER G. MERRITT.

Witnesses:

JOHN BERENDT,
C. H. HALSTEAD.
